THERMOSTATIC SWITCH

Vincent E. O'Neill, Taunton, Mass., assignor to Metals & Controls Corporation, Attleboro, Mass., a corporation of Massachusetts

Application August 10, 1953, Serial No. 373,302

3 Claims. (Cl. 200—113)

This invention relates to thermostatic switches, and in particular to manually resettable trip-free thermostatic switches.

In the manufacture and use of manually resettable trip-free thermostatic switches of the kind disclosed in the John D. Bolesky United States Patent No. 2,199,388, difficulty is sometimes experienced in the adjustment and operation of the push plate (or reset plate) therein which is used to reset the snap-acting thermostat plate after it has opened thermally. The difficulty is experienced when the reset plate shown in said patent is applied to snap-acting elements of the type shown in the Victor G. Vaughn et al. Patent No. 2,317,831. In some cases, both contacts carried by the snap-acting element may not reset at approximately the same time. That is, sometimes so-called "one-ear" action is experienced, namely, that when the reset plate is pushed against the snap-acting element, one side of the element will close first, to be followed by the other side. When this action is encountered, it is found more difficult to adjust the temperature at which the snap-acting element resets to its cold position, and thus the cost of the switch as a whole is increased. In addition, the resetting temperature cannot be calibrated as accurately as desired.

Therefore, it is one object of this invention to provide an improvement over the thermostat shown in said Patent No. 2,199,388 wherein an improved resetting plate is employed.

Another object of this invention is to provide a resetting plate for such thermostats of improved operating characteristics.

A further object of the invention is to provide a reset plate for use in thermostats of the type described, whose construction is such as to render more easily adjustable the resetting temperature of the snap-acting element.

Other objects and advantages will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which two of various possible embodiments of the invention are illustrated:

Fig. 1 is a plan view of one embodiment of the reset plate of this invention;

Fig. 2 is a sectional elevation of the reset plate of Fig. 1, taken in the direction of sight lines 2—2 on Fig. 1;

Fig. 3 is a side view of a thermostat embodying the reset plate of Fig. 1;

Fig. 4 is a bottom view of the thermostat of Fig. 3;

Fig. 5 is a sectional elevation of the thermostat of Fig. 3, taken in the direction of sight lines 5—5 on Fig. 4;

Fig. 6 is a plan view of the Fig. 3 thermostat, with the push-button removed;

Fig. 7 is a plan view of another embodiment of the reset plate of this invention; and

Fig. 8 is a section of the Fig. 7 reset plate taken in the direction of sight lines 8—8 on Fig. 7.

Similar reference characters indicate corresponding parts throughout the several views of the drawings.

Referring now to the drawings for a more detailed description of the invention, numeral 2 indicates a reset plate of this invention, preferably made of steel or some

other rigid metal, although a molded synthetic resin may also be used. A central hole 4 is provided in the plate for the purpose of mounting it (as will be described below) in a thermostatic switch. The plate has been shown in somewhat diamond-like shape, but can have other shapes adapted to fit the particular geometry of the thermostat in which the plate is to be used, if desired.

Provided in the plates are the four raised projections or bosses 6, 8, 10 and 12. As will be described below, these four bosses apply the force and motion of the reset plate, when manually actuated, to four localized areas on the snap-acting plate to reset it. If desired, more bosses may be provided, but four is the minimum.

Referring now to Figs. 3-6, there is shown a thermostat indicated generally by numeral 14 and having a base 16 which is made of electrical insulating material such as Bakelite or other molded resin of proper characteristics. Three stationary terminals 18, 20 and 22 are provided in the base as shown, these terminals being inserted in molded slots in the base, for example, and having overturned heads in the interior of the base to act as stationary contact plates. A threaded adjusting screw 24 is provided in the center of the base 16 (for example, in a threaded hole 26 provided for that purpose). An elongated stem 28 is provided at the upper end of the mounting screw 24, and on stem 28 are respectively mounted a collar 30 and reset plate bushing 32. Bushing 32 slides on collar 30. The turned-over head 34 of stem 28 serves to hold these elements in place in the manner described in the aforesaid United States Patent No. 2,199,388. A thermostatic snap-acting element 36 is held freely but not too loosely on the top of adjusting screw 24 as shown by means of properly spaced shoulders and abutments on the adjusting screw, cooperating with the bottom of collar 30. The reset plate 2 is fastened to the reset plate bushing 32 by means of the shoulder-and-riveted construction 38 as shown, the end of bushing 32 being riveted or swaged over in conventional manner. A reset knob 40, preferably made of electrical insulating material such as Bakelite or other molded resin, is press-fitted to the outside of reset bushing 32 so that actuation of button 32 moves reset plate 2. A compression-type spring 42 is provided inside the reset button 40 to bias the knob 40 upwardly (as drawn). Thus, spring 42 serves to hold the reset plate 2 away from the snap-acting element 36 in its normal position. Other details of the thermostat construction will be found in said U. S. Patents 2,199,388 and 2,317,831.

Referring now to Fig. 6, there is shown a plan view of the Fig. 5 thermostat but with the push button 40 removed in order to show more clearly the relationship between the reset plate 2, the bosses 6, 8, 10 and 12, and the electrical contacts of the switch. As shown in Fig. 6, the inside wall of the base 16 is provided with the recesses 44 which are adapted to receive the ears 46 of the snap-acting element 36 so as to keep the snap-acting element from turning on the adjusting screw 24, and thus keeping contacts 52 and 54 aligned with the co-operating contact faces of terminals 22 and 20, contacts 52 and 54 being welded to snap-acting element 36 as shown. Similarly, recesses 48 are provided which are adapted to receive the ends of the reset plate 2, and keep the latter from turning. (Snap-acting element 36 may be of the kind described in said Vaughn et al. Patent 2,317,831, and as indicated above, has the ears 46 which carry thereon the contacts 52 and 54.) In the cold or closed position of the snap-acting element 36, contact 52 makes electrical connection with the head of terminal 22, and contact 54 makes electrical connection with the head of terminal 20. If desired, an electrical heater 56 may be provided for heating the plate 36, and extends from terminal 20 to terminal 18, the heater being welded to the underneath surface of the turned-over inner heads of these terminals.

In the arrangement shown, it will be observed that bosses 6 and 8 lie on one side of a center line through the center of the thermostat (vertically as drawn), and bosses 10 and 12 lie on the right of said center line. This center line is at right angles to the line joining the contacts 52 and 54. It is also to be noted that the bosses are symmetrically disposed in pairs, the position

of boss 8 corresponding to that of boss 10, and boss 6 to boss 12. With this relationship, it will be observed that the bosses 6 and 8 press on one side of said center line (during a resetting operation) while simultaneously the bosses 10 and 12 are pressing on the other side of the center line. The result of this is to cause both sides of the snap-acting plate to reset almost simultaneously, if not simultaneously. That is, the so-called "one-ear" action is avoided, the reset temperature can be accurately adjusted, and the thermostats are more uniform in their operation. Experience with this construction has shown that it is a simple operation to adjust the temperature of the resetting plate by bending the plate until the correct resetting temperature is obtained.

Referring now to Fig. 7, there is shown another embodiment of the resetting plate of this invention; which differs from the reset plate 2 in that the bosses are not placed within the periphery of the reset plate, but instead are formed in the plate edges. Reset plate 58 again is made of steel or some other rigid metal or material, and has the central hole 60 for the purpose of mounting it as aforesaid. The bosses 62, 64, 66 and 68 are made at the edges of the reset plate, as shown, and in this instance are illustrated as being quarter spheres. Reset plate 58 is used exactly as is the reset plate 2.

In the use of either plate 2 or plate 58, the location of the bosses 6-12 inclusive or 62-68 inclusive is such as to allow that portion of the snap-acting element which includes the ears 46 and an adjacent portion of the non-developable surface of the element to snap to the contact-open position when the snap-acting plate is heated, even though the reset plate is being held at its innermost (or resetting) position. This position is such that the angle made by an imaginary line joining the center of the snap-acting element or plate and any boss, is never greater than 45°. For example, the angle which the line joining boss 6 and the center of the plate 2 makes with the aforementioned center line, is never greater than 45°, and similarly the angle which the line joining boss 8 with the center makes with said center line, is never greater than approximately 45°. Thus, the thermostat is trip-free, that is, the contacts cannot be held in circuit-closing position by the reset knob 40. In addition, it is preferred to have the bosses as far out towards the periphery of the snap-acting plate as consistent with good manufacturing practice, bearing in mind the tolerances normally experienced in making such devices in production. If the bosses on each side of the said center line are placed further apart than shown, that is, each pair nearer the ear of that side of the snap-acting element, it will be found that the force required to reset the snap-acting element to its closed position as it cools becomes less, but on the other hand, the trip-free characteristics of the plate are also diminished. The most desirable setting may be one or the other, depending on what is desired for the operation of the thermostat. However, it is within the realm of mechanical skill to determine which is most suitable. The resetting temperature of the snap-acting element is adjusted by bending the reset plate so that when knob 40 is in its innermost position, the element will be deformed towards its cold position. That is, if it is desired to raise the temperature of resetting, plate 2 (for example) is bent so that when knob 40 is at its innermost position, the bosses will strain the element further to its cold position. To lower the resetting temperature, the reset plate is bent to strain the snap-acting element less toward its cold position.

In view of the above, it will be seen that the several objects of the invention are achieved and other advantageous results attained.

As many changes could be made in the above constructions without departing from the scope of the invention, it is intended that all matter contained in the above description or shown in the accompanying drawings, shall be interpreted as illustrative and not in a limiting sense.

I claim:

1. In the combination of a snap-acting thermostatic element and a rigid reset plate therefor wherein said

snap-acting thermostat carries electrical contacts diametrically opposite each other, means slidably mounting said reset plate on one side of said snap-acting element whereby said plate may be moved toward or away from one surface of said element; a plurality of bosses protruding from that surface of said reset plate which faces said snap-acting element, a first pair of said bosses being on one side of a center line extending through the center of said snap-acting element and approximately perpendicular to a line joining said contacts, and a second pair of said bosses being positioned on the other side of said center line, said paired bosses being positioned on said plate so as to bear against peripheral portions of said element when said reset plate is pushed against said snap-acting element and also being so located that no boss lies on a line through the center of said element which makes an angle greater than approximately 45° with said center line; and means for manually pushing said reset plate against said snap-acting element.

2. A thermostatic device comprising a base; a snap-acting thermostatic element mounted on said base and having two oppositely facing positions of stability in one of which positions it is located relatively closer to said base than it is when in the other position, said thermostatic element passing automatically from its said closer position to its said other position upon change of temperature to a predetermined value, but being incapable, under normal temperature variations, of returning to its said closer position automatically upon subsequent reversal of temperature; first electrical contacts carried on diametrically opposite portions of said element and cooperating with second electrical contacts mounted on said base to make and break an electrical circuit; manually operable means movably mounted with relation to said base and positioned to react against said thermostatic element; and spring means urging said manual means to an extended position away from said element; said manual means including plural means adapted to bear on the surface of said thermostatic element on each side of a center line therethrough when said thermostatic element is in its said other position, to urge said thermostatic element toward its said closer position, said center line being approximately perpendicular to a line joining said first electrical contacts, and said plural means comprising a plurality of bosses extending from said manual means and overlying said thermostatic element, none of said bosses lying on a line through the center of said element which makes an angle greater than approximately 45° with said center line.

3. A manually-resettable snap-acting thermostatic switch comprising a base; stationary contacts on said base; a snap-acting thermostatic element mounted on said base and having two oppositely facing positions of stability in respect to said base, in one of which it is nearer to the base than when in the other; electrical contacts mounted on said element and electrically engaging said stationary contacts when the element is in its said nearer position; a rigid reset plate movably mounted on said base and movable toward and away from the thermostatic element, said plate having four bosses on its surface extending toward said element, two of said bosses being on one side of a line through the center of said plate which is approximately perpendicular to a line joining said contacts on said element, and the other two being on the other side thereof, said bosses being spaced equi-distantly from the center of said thermostat plate and contacting the latter on peripheral portions thereof with none of said bosses lying on a line through the center of said plate which makes an angle greater than approximately 45° with said center line; and means for manually moving said reset plate toward said element.
